UNITED STATES PATENT OFFICE.

SAMUEL K. BAYLEY, OF BOSTON, MASSACHUSETTS.

HEAT INSULATION OF REFRIGERATOR CARS AND BUILDINGS.

SPECIFICATION forming part of Letters Patent No. 284,361, dated September 4, 1883.

Application filed January 18, 1883. (No model.)

To all whom it may concern:

Be it known that I, SAMUEL K. BAYLEY, of Boston, county of Suffolk, and State of Massachusetts, have invented certain Improvements 5 in Insulation of Refrigerator Cars and Houses, of which the following is a specification.

My invention consists in the combination of hair felt and paper with dead-air spaces for a non-conducting filling.

10 In the accompanying drawings, Figure 1 is a section of the roof and trap. Fig. 2 is a section of the floor. Fig. 3 is a section of the sides.

Fig. 1 is a sectional view of the roof, and 15 also shows parts of the trap or door of the same. E E is the customary double boarding used when tin is not applied; C, an air-space; B, paper; A, hair felt; B', paper; F, the carling; B², paper; A', hair felt; B³, paper; C, 20 air-space; D, sheathing or inside lining. Fig. 1 also shows the trap, having a covering-door, J, which is fastened by a hinge, so as to be swung open. Beneath this is the trap, which is made first of sheathing D, then paper B, 25 hair felt A, paper B', air-space C inside of frame of trap, paper B², hair felt A', paper B³, and sheathing or lining D, forming a groove around the edge for a cushion, to be filled with any flexible material to make a tight joint.

30 Fig. 2 is a section of the floor just above one of the stringers K, on both sides of which are placed strips of wood for false or bottom floor, the top of this false floor M coming flush with the top of stringer K. On top of this 35 floor is placed a course of paper, B', hair felt A', paper B', hair felt A, paper B, strip of wood and air-space C, and floor H. Another course of paper can be put on top of the wood strip and the air-spaces C.

40 Fig. 3 shows a section of the walls. The sheathing D has beneath it paper B, the framing-posts and air-spaces C, paper B', hair felt A, paper B², hair felt A', paper B³, wood and air-spaces C, and finally the inner sheathing 45 or lining, D. The paper B³ can be put on inside of air-space next the sheathing, if desired. All the edges of the paper should be gummed or made fast together, so as to make one continuous piece, and all outside paper 50 ought to be painted or covered with any suit-

able water-proof material, or else prepared "water-proof," so as to prevent dampness from rotting it, and thus destroying its insulating properties.

The foregoing description of the component 55 parts of the roof, floor, and sides of a car or room, as shown in Figs. 1, 2, and 3, embraces the general arrangement of the elements of wood, paper, hair felt, and air-spaces, or their respective equivalents, which I find to give the 60 most perfect insulation; but of course they can be modified without interfering with the principle of their combination described, which I will explain. Dead-air spaces, while the hardest to obtain, give the most perfect insulation. 65 I find that hair felt, which is porous, and a non-conductor of heat or cold, when dry, placed between two layers of paper or its equivalent for making an air and damp proof chamber, furnishes the most easily-constructed, 70 durable, and practicable dead-air space. The use of hair felt alone for this purpose is not new; but its use between damp-proof walls I believe to be new. I find that hair felt will absorb dampness, and that when damp it is 75 no longer a good non-conductor of heat and cold. I use paper as the cheapest and easiest applied material for making such walls, but do not limit myself to it.

Instead of hair felt, any other material having like non heat and cold conducting properties can be used between the aforesaid damp-proof walls.

By returning to Fig. 1 it will be seen that I have two confined-air spaces, C, and two dead-air spaces, A and A'. For the floor, Fig. 2, I have one confined-air space, C, and two dead-air spaces, A and A', and for the sides, Fig. 3, I have two confined-air spaces, C, and two dead-air spaces, A and A'. 80 85 90

As the paper comes in narrow strips compared with the surface of the side, top, or bottom of a car, for example, in applying it I use the longest lengths possible without cutting. I lap edges and securely fasten them by 95 gumming, glueing, or pasting, so that the entire car will, as it were, be covered with one sheet without openings, except at the doors and traps. In like manner I should apply any material the equivalent of paper for the 100

purpose specified. Since the felt comes in sheets, in order to avoid the use of tacks or equivalent for holding its edges in place and close together, as they would penetrate the paper wall, and thus injure its insulating and damp-proof properties, I secure said edges of the felt in place by attaching them to the paper with glue, paste, or their equivalent. With an insulating-wall of other than paper, or in places where the felt edges cannot be secured to the same, I butt the edges of the felt sheet and secure them by a covering-strip of any suitable material glued or otherwise attached to them.

15 Water is generally used for cleansing refrigerator rooms and cars; hence a necessity for making the linings for the dead-air spaces, where practicable, damp-proof. Care should be used that the paint or material used for 20 making the linings damp-proof are inodorous and non-absorbents of odors.

In the drawings the spaces C are simply confined-air chambers. I call them "confined" because boarded on one or more sides, in contradistinction to dead-air chambers, which have a porous filling, that prevents the air from being agitated, and which practically have damp or air proof walls, or both. By combining the confined with the dead air spaces I 30 find the insulating properties of the walls are greatly increased.

I find that finishing the inner lining of a refrigerator with oil of any kind is detrimental to the preservation of its contents. Fruits

will taint in a night; meats also. To avoid 35 this I use shellac or its equivalent.

What I claim as new, and desire to secure by Letters Patent, is—

1. Securing the edges of felt sheets together to form in effect a continuous sheet through 40 the walls, top, or bottom of a refrigerator-car or refrigerator structure by the use of an adhesive substance, substantially as and for the purpose described.

2. The combination, in the walls of a 45 refrigerator-car, of an outer and an inner sheathing, with the intervening air-space divided vertically into two or more air-spaces by a partition composed of two or more sheets of heavy hair felt, with its edges secured together, as 50 specified, and with coverings and alternate layers of paper, with its edges secured as specified, forming continuous and unbroken sheets the full size of the walls, substantially as described.

3. The combination, in the roof of a refrigerator-car, of the following elements in the order substantially as named from the top downward: single or double sheathing, air-space, paper formed into a continuous sheet 60 the full size of the roof, felt of similar extent, formed by securing its edges as specified, paper, carling, paper, felt, paper, air-space, and inner sheathing made air and damp proof.

SAML. K. BAYLEY.
